Primary Examiner—Stella M Reid*Assistant Examiner*—Elizabeth J Oswecki(74) *Attorney, Agent, or Firm*—David D. Brush; Westman, Champkin & Kelly P.A.(57) **CLAIM**

The ornamental design for a spray bottle fill port, as shown and described.

DESCRIPTION

FIG. 1 is a perspective view of a spray bottle fill port showing my new design;

FIG. 2 is a left side view thereof;

FIG. 3 is a right side view thereof;

FIG. 4 is a rear elevational view thereof;

FIG. 5 is a front elevational view thereof;

FIG. 6 is a top plan view thereof; and,

FIG. 7 is a bottom plan view thereof.

Features illustrated with dash lines are not considered features of the invention being claimed, but rather illustrate an exemplary environment for the claimed features illustrated with solid lines.
